CLAIM

The ornamental design for an incontinence sensor brief, as shown and described.

DESCRIPTION

FIG. 1 is a top view of an incontinence sensor brief in accordance with the present design;

FIG. 2 is a bottom view thereof;

FIG. 3 is a right view thereof;

FIG. 4 is a left view thereof;

FIG. 5 is front view thereof;

FIG. 6 is rear view thereof; and,

FIG. 7 is a front perspective view of the incontinence sensor brief showing an alternate configuration for a state of use, coupled in accordance with the present design.

The broken lines provided herein show portions of the incontinence sensor brief that form no part of the claimed design. The diagonal hatching provided herein illustrate a claimed transparent layer.

1 Claim, 4 Drawing Sheets
